CLAIM

The ornamental design for an electric food dispenser, as shown and described.

DESCRIPTION

FIG. 1 is a front right perspective view of an electric food dispenser showing my new design.

FIG. 2 is a left side view thereof;

FIG. 3 is a right side view thereof;

FIG. 4 is a front view thereof;

FIG. 5 is a rear view thereof;

FIG. 6 is a bottom view thereof; and,

FIG. 7 is a top view thereof.

The broken lines in the figures show portions of the electric food dispenser which form no part of the claimed design.
